UNITED STATES PATENT OFFICE.

JACOB LANE AND NELSON McPHERSON, OF GAINSBOROUGH, ONTARIO, CANADA; SAID LANE ASSIGNOR TO EPHRAM McPHERSON, OF SAME PLACE.

LOAD-ELEVATOR.

SPECIFICATION forming part of Letters Patent No. 390,787, dated October 9, 1888.

Application filed December 21, 1885. Serial No. 186,318. (No model.) Patented in Canada October 28, 1885, No. 22,690.

To all whom it may concern:

Be it known that we, JACOB LANE and NELSON McPHERSON, citizens of the Dominion of Canada, residing in the township of Gainsborough, in the county of Lincoln and Province of Ontario, have invented a new and useful Load-Elevator, (for which we have obtained a patent in the Dominion of Canada, No. 22,690, bearing date October 28, 1885,) of

to which the following is a specification.

Our invention is an improved load-elevator; and it consists in certain improved constructions and combinations of parts, as will be hereinafter described and claimed.

15 In the drawings, Figure 1 is a perspective view of our improvement as in use, and Fig. 2 is a detail view of one of the combined drums and ratchet-wheels.

The framing may be an ordinary barn-framing, or may be of any other suitable construction. In this framing we journal the parallel shafts A B, to each of which we attach at one end the load-suspending cords C, which depend from the shafts A B and connect at their 20 lower ends with the parallel bars D, supporting the parallel bars D', which may be adjusted under the wagon-body, as shown. On each of the shafts A B are secured a drum, E, and a ratchet-wheel, F, which are combined 25 and arranged, preferably, at the ends of the shafts, as shown.

Pawl G G are pivoted at one end to the framing and engage with the ratchet-wheels F. These pawls and the ratchet form a 30 detent, as will be understood. The releasing-cords g connect with the pawls and are directed thence by suitable guides into convenient reach of the operator. A cord, H, connects the drums E E together, so the proper turning 35 of one will effect also the desired turning of the other. The operating-cord h extends from one of the drums E, as shown, and is by preference formed integral with the connecting-cord H, such cord H h being wound on

the drum from which part h depends, as will 45 be understood from the drawings.

It will be seen that by properly connecting the suspension-cords with the wagon-body and then drawing on power-cord h the load may be elevated to any desired point and will be 50 stopped thereat by the detent. On releasing the detent the load may be lowered, as desired.

The particular construction of the combined drum and ratchet-wheel is most clearly shown 55 in Fig. 2. The spoke-bars 1 2 are arranged at right angles to each other and extend out to the periphery of the drum, of which periphery their ends and also the ends of the short radial bars 3 form a part. Between the ends of 60 bars 1, 2, and 3 the peripheral sections 4 are secured. A ring, 5, is secured on the inner side of the drum and extends radially beyond the periphery thereof, forming a guard-flange. On the other end of the drum we secure the 65 ratchet-wheel sections 6, which taper inward toward their inner ends and have their outer ends shaped to provide the ratchet-teeth.

The suspending-cords C connect at their 70 lower ends with the parallel side bars, D, on which the ends of the parallel cross-bars D' are rested. These cross bars D' extend under and support the wagon-body, as clearly shown in Fig. 1.

Having thus described our invention, what 75 we claim as new is—

In an apparatus, substantially as described, a combined drum and ratchet-wheel, the said ratchet-wheel being formed of inwardly-tapering sections, all substantially as and for 80 the purpose specified.

Gainsborough, September 23, 1885.

JACOB LANE.
NELSON McPHERSON.

In presence of—

D. E. CAULTON,
S. R. BADGLEY.
